UNITED STATES PATENT OFFICE.

PAUL RECKOW, OF CHICAGO, ILLINOIS.

METHOD OF VENEERING.

1,007,973.

Specification of Letters Patent.

Patented Nov. 7, 1911.

Application filed March 27, 1911. Serial No. 617,062.

To all whom it may concern:

Be it known that I, PAUL RECKOW, a citizen of the United States, residing at Chicago, in the county of Cook and State of Illinois, have invented a certain new and useful Improvement in Methods of Veneering, of which the following is a full, clear, concise, and exact description, reference being had to the accompanying drawings, 10 forming a part of this specification.

My invention consists of an improved method of preparing veneers before applying them to supporting base pieces. Heretofore in the art, it has been customary to take thin wood veneers and glue them to the supporting boards without specially preparing the veneers, and it has been found that owing to the thinness of the veneers and the open pores characteristic of many woods, the 15 glue thus used is forced through the pores of the veneer and not only spoils the finished effect of the veneer and causes the finished surface to go "dead" after a time, but the glue finds its way in considerable 20 quantity onto the outer surface of the veneer during the operation of pressing the veneer and base during the drying of the glue, and thus a considerable amount of work is required to remove the glue from the outer 25 surface of the veneer and the veneer is correspondingly reduced in thickness.

By my process, I treat one side of the veneer with a water proof solution which, after drying, is applied to the board by 30 means of glue in the usual manner. The water proof solution serves to effectually close the pores on the inner surface of the veneer without penetrating the veneer to any appreciable degree, and when dry serves to 35 effectually prevent the glue from entering the pores of the veneer without in any way interfering with the adhesion between the glue and the veneer. As a result, the veneer thus applied may be finished in precisely 40 the same manner and with precisely the same effect as boards made of the corresponding wood, and the finish thus given the veneer besides being the regular finish of the wood, is durable inasmuch as it is not subject to 45 the deteriorating effect of the glue as in previous veneered structures. I refer particularly to the use of a water proof solution for treating the under side of the veneer as it has been proposed to use fillers of differ- 50 ent kinds upon the under side of the veneer

before gluing the same to the supporting board. Such fillers are invariably mechanical mixtures of solid matter in finely divided condition mixed with liquid of one kind or another, as a result of which the solid matter 55 may be worked into the pores of the veneer and left there until the liquid portion of the mixture has evaporated or soaked into the veneer to a certain extent. By my process the water proof solution employed protects 60 the entire under surface of the veneer without perceptibly filling the pores, thus leaving the pores of the veneer free to receive the desired filler upon the outer surface in the usual manner employed in finishing the 65 wood.

Figure 1 shows in cross-section a core board to either side of which a piece of veneer is secured which has been treated in accordance with my process. Fig. 2 shows 70 in a view similar to Fig. 1 an enlarged cross-section of a small portion of the veneer to indicate the relation of the water-proofing film to one of the pores in the veneer.

In carrying out my invention the veneer 75 1 which may be applied either to one side or both sides of the board 2 is first coated upon its under surface with a water proof solution which when it dries, leaves a thin film of water proof material 3 extending 80 over the inner surface of the veneer in a position to close the pores of the same. The board 2 constituting the base for supporting the veneer may either be a single piece or as 85 is common in many constructions, it may be 90 built up of laminations to prevent it from warping, and in either case it is given a coating of glue 4 and the treated veneer is then applied and held in place by means of 95 a suitable press until the glue has dried. The result is a veneered board having all 100 of the characteristics of the natural wood which may be finished as desired. The glue, which is very hygroscopic, is thus protected from the action of moisture and prevented from conducting the moisture to the under side of the finish on the outer surface of the veneer. While many water proof solutions may be employed for treating the 105 surface of the veneer, I have found that a neutral solution of camphor and soluble cotton in amyl acetate and alcohol serves admirably for this purpose. The soluble cotton may be dissolved either in alcohol, acetone or amyl acetate as desired and if pre- 110

ferred, the solution may be made by dissolving celluloid in one of the solvents mentioned.

In the past in pressing the veneered boards during the drying of the glue, it has been customary to insert between the veneered surfaces heated "cauls" or boards having greased surfaces to prevent their sticking to the veneers. It was then necessary after taking the veneered boards from the press to wash them to remove the grease and scrape them to remove the glue. By my process this labor is entirely eliminated as it is not necessary to grease the cauls and therefore the veneers need not be washed after the veneered boards are taken from the press, and the scraping operation is entirely eliminated by carefully preparing the surface of the base or core stock employed so that it is true. In this way the amount of work required to prepare the surface of the veneer for receiving the finish is reduced to a minimum and the full thickness of the original veneer is left to receive the finish and stand the possible refinishing operations to which the veneered surface may be subjected, when after long use such refinishing becomes necessary.

A further result secured by my invention consists in the protection afforded the veneer by the water-proof film upon its back, as a result of which swelling and shrinking of the veneer is prevented. This protection which prevents shrinkage of the veneer is particularly valuable in that it prevents the fading away of the varnish used in finishing the veneer. In the past considerable difficulty has been experienced in this connection since veneers have very commonly shrunk after being finished, with the result that the finish of the varnish has become checked, thus causing the fading away of the finish mentioned.

It is to be understood that the veneer treated as described may be applied to a supporting base of any description which is susceptible of being veneered regardless of whether the surface of the base is flat or of other conformation.

While I have found it preferable to treat the inner surface of the veneer with the water-proof solution, I have also found that similarly treating the outer surface or even dipping the veneer in the water-proof solution, effectually prevents the glue from penetrating through the pores to the outer surface of the veneer to interfere with the finishing of the same. Whether the veneer is treated in one way or another as described above, it may be filled and finished after the glue is dry in substantially the same manner as though it were the solid

wood, the essential thing being to have a film of water-proof material between the glue and the finish. A result secured by thus coating the veneer with a water-proof solution is indicated in Fig. 2 which is an enlarged cross-sectional view through one of the pores in the veneer. In this figure the veneer 1 is shown as coated with the water-proof compound 3, which extends into one of the pores 1^a of the veneer and across the pore at 3^a. The exact position of the partition 3^a across the pore 1^a is of little moment and is determined by the relative rapidity of drying of the two sides of the veneer. Fig. 2 represents the veneer after the solvent has entirely evaporated leaving the protective film upon the veneer. It is to be borne in mind that since the solvent is extremely fluid, the pores will be nearly or completely filled with the liquid when it is applied, and that in connection with woods usually treated by my process the partitions 3^a across the pores 1^a will usually be about centrally located as indicated. Instead of being a disadvantage, I find that this is a marked advantage since besides leaving the pores open on their outer surface for receiving the filler used in the finishing operation, the pores are left more or less open on their under side, which results in positive engagement between the veneer and the glue.

What I claim is:

1. The process of forming a veneered structure which consists in coating a surface of the veneer with water-proof solution and gluing the treated surface to a supporting base.
2. The process of forming a veneered structure which consists in coating a surface of the veneer with a solution of cotton and camphor in amyl acetate, alcohol and acetone, and gluing the coating and veneer to a supporting base.
3. The process of forming a veneered structure which consists in coating a surface of the veneer with a solution of celluloid in acetone, and gluing the coating and veneer to a supporting base.
4. A veneered structure which comprises a core, a veneer coated with a water-proof compound extending partly into and across the pores of the veneer and having its coating secured to the core by means of glue.

In witness whereof, I hereunto subscribe my name this 23rd day of March, A. D., 1911.

PAUL RECKOW.
